W. E. PORTER

CLOCK MOVEMENT

Filed March 7, 1923

Inventor.
Wilson E. Porter
Seymour & Garce
Attn:

UNITED STATES PATENT OFFICE.

WILSON E. PORTER, OF NEW HAVEN, CONNECTICUT, ASSIGNOR TO NEW HAVEN CLOCK CO., OF NEW HAVEN, CONNECTICUT, A CORPORATION.

CLOCK MOVEMENT.

Application filed March 7, 1923. Serial No. 623,311.

To all whom it may concern:

Be it known that I, WILSON E. PORTER, a citizen of the United States, residing at New Haven, in the county of New Haven and State of Connecticut, have invented a new and useful Improvement in Clock Movements; and I do hereby declare the following, when taken in connection with the accompanying drawings and the characters 10 of reference marked thereon, to be a full, clear, and exact description of the same, and which said drawings constitute part of this application, and represent, in—

Fig. 1 a view in front elevation of one 15 form which a clock-movement embodying my invention may assume.

Fig. 2 a reverse plan view thereof.

Fig. 3 a broken, perspective view, showing 20 the lower portions of the movement plates as mounted but stripped.

Fig. 4 a detached, perspective view of the removable bridge.

Fig. 5 a sectional view on the line 5—5 of 25 Fig. 1.

Fig. 6 a corresponding view with the bridge removed, and a spring-barrel unit drawn forward, preparatory to its removal, without demounting the plates.

My invention relates to an improvement 30 in clock-movements, the object being to adapt the same at a low cost to have their spring-barrel units removed and replaced without demounting the movement-plates.

With these ends in view, my invention 35 consists in a clock-movement having certain details of construction and combinations of parts as will be hereinafter described and particularly pointed out in the claims.

In carrying out my invention, as herein 40 shown, I have applied it to a chime-clock movement having a front movement-plate 10 and a rear movement-plate 11, united in the customary manner by pillars 12. Between these plates are three removable 45 spring-barrel units respectively employed for driving the time, strike and chime trains, none of which are shown, but which may be of any approved construction. The purpose 50 of my invention is to provide for removing and replacing these units, as may be required, without demounting the plates 10 and 11, and so disturbing the several trains of the movement. Each of these units consists, as shown, of a barrel 13, a main-wheel 55 14, an arbor 15, and a ratchet-wheel 16 hav-

ing, upon its inner face, a bearing-hub 17, and upon its outer face a bearing-hub 18. For the reception of the trunnion 19 at the inner end of each of the arbors 15, the rear movement-plate 11 is provided with three 60 small bearing-holes 20 to complement which the front movement-plate 10 is formed with three keyhole slots having their circular inner ends 21, respectively, concentric with the said bearing-holes 20, the straight outer 65 ends 22 of the said key-hole slots being wide enough for the passage through them, in either direction, of the outer ends of the arbors 15, as will be described hereinafter. The circular bearing-hubs 17 of the respective ratchet-wheels 16 are adapted in diameter to have bearing in the circular portions 21 of the key-hole slots aforesaid.

To normally maintain the removable units in proper position, I employ a removable 75 segmental bridge 23 secured by screws 24 to spacing-studs 25 in the front movement-plate 10, whereby a narrow space is formed between the said bridge and the plate for the reception of the ratchet-wheels 16, the circular bearing-hubs 18 of which enter and have bearing in bearing-holes 26 in the bridge, which is also perforated as at 27 for the reception of the screws 24, and has, as 80 shown, a clearance-opening 28 which provides clearance for the stud 29 of the pawl 30 co-acting with the ratchet-wheel 16 of the intermediate spring-barrel unit, as shown in Fig. 1. Each of the main arbors 15 is formed with a spacing-shoulder 31, upon 85 which its ratchet 16 rests, thus providing a take-down space 32 between the main-wheels and the front movement-plate of sufficient depth to permit any unit to be pulled forward sufficiently to disengage its trunnion 90 19 from its bearing-hole 20 in the rear movement-plate.

As an illustration of the use of my invention, it may be assumed that one of the three main springs has been broken, or has been 100 otherwise deranged. Now, instead of demounting the entire movement, as would be necessary under ordinary circumstances, it is necessary only to remove the bridge 23, after which the unit requiring attention is 105 pulled forward a distance represented by the space 32, whereby its position, as shown in Fig. 5, is changed into the position in which it is shown in Fig. 6, in which latter the trunnion 19, at the rear end of the arbor 15, 110

is seen to be disengaged from its bearing-hole 20, in the rear movement-plate 11, and the bearing-hub 17, upon the inner face of the ratchet-wheel 16, disengaged from the 5 circular portion 21 of the key-hole slot of the given unit. The unit is now free to be drawn laterally outward in the direction of the arrow 33, from its position between the two movement-plates, which are left 10 entirely undisturbed. At this time, the shoulder 31 of the arbor passes outward through the straight narrow portion 22 of the appropriate key-hole slot. Another way of removing the unit would be to first remove 15 the bridge, then slip the ratchet-wheel off the squared end of the main-arbor of the unit and then lift the unit, so as to clear its trunnion 19 from the bearing-hole 20, after which it may be drawn laterally from its 20 position between the two movement-plates. To return the unit, the reverse of the steps above described must be taken.

I have illustrated my invention as applied to a chime-clock having three spring-barrel units, and a single bridge to hold them in place, as well as to provide support for the outer ends of their arbors, but my invention is equally applicable to clocks having only one or two spring barrel units, in which case 25 the bridges would be correspondingly altered without any change in principle, my invention being particularly characterized by the employment of a removable bridge, which not only provides a support and bearing 30 for the outer end of the arbor of a removable spring-barrel unit, but also serves to hold the spring-barrel unit against endwise displacement. My invention is further characterized by providing a double bearing 35 for one end of the arbor,—namely, in a movement-plate and in the bridge affixed thereto.

I claim:

1. In a clock-movement, the combination 40 with the front and rear movement-plates thereof, of a bridge adapted to be applied in spaced relation to one of the said plates,

and a removable spring-barrel unit provided with a ratchet-wheel the said ratchet-wheel adapted to have bearing in one of the 50 said movement plates and also in the bridge affixed thereto.

2. In a clock-movement, the combination with the front and rear movement-plates thereof, one of the said plates being formed 55 in its edge with a key-hole slot and the other plate being formed with a bearing-hole concentric with the circular inner end of the said slot; of a bridge adapted to be applied in spaced relation to the slotted plate and 60 having a bearing-hole concentric with the circular inner end of the said slot; and a removable spring-barrel unit provided with a ratchet-wheel having upon its inner and outer faces bearing-hubs; of which the inner 65 hub has bearing in the circular portion of the said slot, and the outer hub bearing in a concentric bearing-hole in the bridge.

3. In a clock-movement, the combination with the front and rear movement-plates 70 thereof, the outer plate having a plurality of key-hole slots formed in its edge and the inner plate having a plurality of concentric bearing-holes; of a bridge adapted to be applied in spaced relation to the front movement-plate and having bearing-holes concentric with the bearing-holes in the inner plate, and with the circular portions of the key-hole slots in the outer plate, and a plurality 75 of removable spring-barrel units provided with ratchet-wheels, each having an outer and an inner bearing-hub, the outer bearing-hubs of the said wheels fitting into the bearing-holes in the bridge, and the inner bearing-hubs of the said wheels fitting into the 80 circular portions of the key-hole slots in the front movement-plate.

In testimony whereof, I have signed this specification in the presence of two subscribing witnesses.

WILSON E. PORTER.
